CLAIM

The ornamental design for a motorcycle battery connector, as shown and described.

DESCRIPTION

FIG. 1 is a top, left, front perspective view of a motorcycle battery connector showing our new design; and,

FIG. 2 is a top plan view thereof.

The uniform broken line showing in FIGS. 1-2 is for the purpose of illustrating portions of the motorcycle battery connector and forms no part of the claimed design.

1 Claim, 2 Drawing Sheets

FIG. 2
